UNITED STATES PATENT OFFICE

139,434

DESIGN FOR A CUBICLE FOR ELECTRICAL CONTROL PANELS

Kibbey W. Couse, Newark, N. J.

Application May 9, 1944, Serial No. 113,528

Term of patent 14 years

(Cl. D26—5)

To all whom it may concern:

Be it known that I, Kibbey W. Couse, a citizen of the United States, residing at Newark, in the county of Essex, State of New Jersey, have invented a new, original, and ornamental Design for a Cubicle for Electrical Control Panels, of which the following is a specification, reference being had to the accompanying drawings, forming a part thereof.

In the drawings:

Figure 1 is a perspective view of the cubicle for electrical control panels, showing my new design.

Figure 2 is a view of Figure 1, looking at the left-hand end, the cubicle doors being closed.

Figure 3 is a top plan view of Figure 1 with the end doors in open position.

Figure 4 is a view of Figure 2 with the cubicle doors in open position.

Figure 5 is a view of the front side of Figure 1.

Figure 6 is a view similar to Figure 5, but looking at the opposite side of the cubicle.

Figure 7 is a view of Figure 1, looking toward the right-hand end, but with the cubicle doors in closed position.

Figure 8 is a view of Figure 7, but with the cubicle doors in open position.

I claim:

The ornamental design of a cubicle for electrical control panels, as shown.

KIBBEY W. COUSE.
